UNITED STATES PATENT OFFICE.

JOSEPH G. MOOMY, OF ERIE, PENNSYLVANIA, ASSIGNOR TO THE TAPER SLEEVE PULLEY WORKS, OF SAME PLACE.

WOODEN PULLEY.

SPECIFICATION forming part of Letters Patent No. 406,402, dated July 2, 1889.

Application filed December 14, 1888. Serial No. 293,562. (No model.)

To all whom it may concern:

Be it known that I, JOSEPH G. MOOMY, a citizen of the United States, residing at Erie, in the county of Erie and State of Pennsylvania, have invented certain new and useful Improvements in Wooden Pulleys; and I do hereby declare the following to be a full, clear, and exact description of the invention, such as will enable others skilled in the art to 10 which it appertains to make and use the same.

This invention relates to wooden split pulleys; and it consists in certain improvements in the construction thereof, as will be herein-15 after fully set forth, and pointed out in the claims.

The invention is illustrated in the accompanying drawings, as follows:

Figure 1 is a side elevation of a completed 20 pulley made in accordance with my invention. Fig. 2 is an elevation view of one of the halves of the pulley looking from the position of the removed half. Fig. 3 is an elevation view of the face of the pulley. Fig. 4 25 is a side view of that part of the pulley-rim which is formed of the rings $a' a' a'$. Fig. 5 is an elevation view of one of the halves of the part shown in Fig. 4, looking from the point occupied by the removed half. Figs. 6 30 and 7 show details of construction, and will be explained in place herein.

Like letters of reference indicate corresponding parts in all the figures.

The construction is as follows: The pulley-rim is made up of rings formed of segments, as is common in this class of pulleys. The central part of the rim is composed of as many rings as desired—say three, as in the drawings, marked $a' a' a'$ —and the remainder 35 of the rim is composed of finishing-rings $a a$. The spokes of the pulley are composed of two cross-bars $B B$, which lie parallel with each other, one in each section of the divided pulley. On the sides of the bars B toward 40 the shaft or center of the pulley are two blocks $C C$, one on each side of the shaft or center of the pulley, and, preferably, equally distant therefrom. These blocks are preferably laid with the grain of the wood across the grain of 45 the wood of the bars B ; but this is not material, and they are let into the bars B slightly.

The bolts $D D$, which hold the sections of pulley together, pass through the bars B and blocks C . In the square central space H , formed by the bars $B B$ and blocks $C C C C$, 55 there will be used such bushing-blocks as may be desired. These bushing-blocks are not shown in the drawings, as they form no part of this invention. The blocks $C C$ on the opposite arms will be made sufficiently short so 60 as not to set upon each other when the pulley is assembled, thus leaving the bars free to be slightly sprung by the bolts $D D$ when the pulley is being clamped upon the shaft.

The manner of inserting and securing the 65 bars B is as follows: After the middle part of the rim is formed by gluing the rings $a' a'$ a' together, holes E are bored, as shown in Fig. 1, and the ring is then cut in two by a straight saw-cut S , which passes through the 70 holes E diametrically. The halves of the middle part of the rim are then both cut by a saw, removing the piece b' , and leaving the right-angled notch b , as seen in Fig. 6. The spoke-bars B are then put into the segments 75 by seating them in the notches b , as seen in Fig. 7. Dowels b^4 are put through the bars and into the segments, as shown, and the pieces b' are cut down to form the pieces b^2 , which are put in place over the ends of the 80 bars B and secured by glue and dowels b^3 . Round pieces E' are secured in the spaces formed by the holes E , as shown in Fig. 7, and the divided parts are again put together and the finishing-rings $a a$ are put on as 85 commonly. After the pulley-rim has thus been completed, with the arms B embedded therein, I put in dowels $F F$, which pass entirely through the rim in a diagonal direction. These dowels, like all the others, are put in 90 with glue, and they are set diagonal to the line of the shaft, so as to hold the rings $a' a'$ a' against lateral separation, somewhat in the manner of a dovetail.

It will be seen that there are no nails or 95 screws used in the pulley, which is an advantage in many respects.

After the pulley is completed, as described, the finishing-rings are cut by a saw, so that the pulley will divide on the line $S S$. 100

I am aware that split wooden pulleys have been made by first making up the middle

part of the ring, then dividing that part, then putting in the spoke-arms, then putting on the finishing-rings, and then dividing said rings so the pulleys will bisect, as described, 5 and I shall therefore not claim these features of construction broadly.

What I claim as new is—

1. The combination, in a split wooden pulley, of a central rim part composed of the 10 rings a' , divided on the line S S and having the notches b cut therein, the spoke-bars B, seated in said notches, the pieces b^2 , filling said notches, the finishing-rings a a , completing the rim and divided so as to bisect the 15 pulley on the line S S, and the blocks C C on said spoke-bars.

2. The combination, in a wooden split pulley, of a central rim part formed of the rings

a' , divided into segments and having the notches b cut at the ends of each segment, the 20 spoke-bars B B, seated in said notches and secured by dowels b^4 b^4 , the piece b^2 , formed from the pieces b' , filling the notches b , the dowels b^3 , holding said pieces b^2 and the bars B in place, and the finishing-rings a , completing 25 said pulley-rim.

3. In a wooden split-pulley, the combination, with the rim A, spoke-bar B, and filling-piece b^2 , of the dowels b^3 and b^4 , entering said rim at right angles to each other. 30

In testimony whereof I affix my signature in presence of two witnesses.

JOSEPH G. MOOMY.
